JOSEPH W. LEGG, OF WILKINSBURG, PENNSYLVANIA, ASSIGNOR TO WESTINGHOUSE ELECTRIC & MANUFACTURING COMPANY, A CORPORATION OF PENNSYLVANIA

SURGE RECORDER

Application filed July 19, 1924. Serial No. 727,040.

My invention relates to electrical surge recorders and particularly to devices for recording steep-wave-front voltage surges.

One object of my invention is to provide a device of the above indicated character that shall be simple, compact and durable in construction and easy to manipulate.

Another object of my invention is to provide a surge recorder that shall be economical to manufacture and effective in its operation.

In copending application Serial No. 680,569, filed December 13, 1923, by J. F. Peters, and assigned to the Westinghouse Electric & Mfg. Company, is set forth an instrument for recording steep-wave-front voltage surges, according to the principles of which my present invention operates and to which reference may be had for a better understanding of my invention.

As disclosed in the copending application, variations in certain electrical quantities may readily be observed by the movement of a galvanometer element. However, there are certain other electrical phenomena which occur so quickly that the lightest known galvanometer element will not respond thereto.

As disclosed in the copending application, when an electrode engaging a grounded sensitized plate, such as a light-sensitive or photographic plate is subjected to certain high-voltage surges, figures will be recorded on the plate from which the direction, magnitude and duration of the surge and the steepness of the wave front thereof may be determined.

The device of the copending application shows the electrode as stationary and the sensitized plate as rotatable relative thereto in order that the position of the surge figure upon the plate may provide an indication of the time that the surge occurred.

It is desirable in devices of this character, to employ standard photographic plates which are of rectangular shape. In order to utilize the maximum area of the plate for effecting records, it is desirable in the first instance, to have the electrode and the plate move relatively so that a circle of maximum diameter may be described by the electrode over the surface of the plate. This object

may be accomplished more effectively and the space, occupied by the instrument as a unit, be reduced to substantially a minimum, considering the voltages employed and other factors of construction, by providing a stationary sensitized plate and having the electrode rotate relative thereto. Thus, the annular space that would be required in which to rotate the corners of the plate, were the plate rotatable, is conserved and the instrument rendered more compact.

Other features, such as a novel plate holder having means for maintaining a uniform space between the electrode and a ground plate or sheet beneath the sensitized plate and means for recording the surges in chronological order, assist in rendering the device of my invention compact in construction, easy to manipulate and effective in its operation.

Figure 1, of the accompanying drawings, is a view, partially in side elevation and partially in section, of a surge recorder constructed in accordance with my invention, and

Fig. 2 is a bottom view, taken along the line II-II of Fig. 1.

The device embodying my invention comprises, in general, a light-proof casing 1, a motive device or clockwork mechanism 2 disposed therein, a rotatable member or insulating disk 3 for actuation by the mechanism 2, an electrode 4 carried by the member 3, an annular contact member or slip ring 5, carried by the disk 3, a terminal member 7, a stationary contact member 8, mounted on the terminal member 7 for engagement with the annular contact member 5 and a plate holder 10.

The casing 1 preferably comprises a sheet-material side-wall member 12, an insulating top-wall member 14, secured thereto, as by screws 15, and a bottom wall member 16 having an opening 17 therein. The opening 17 is preferably of circular shape and sufficiently larger than the disk 3 to permit ready access thereto, when the plate holder 10 is not in position.

The clockwork mechanism 2, of a usual form, is provided for the purpose of driving the electrode 4 and is preferably suit-

ably secured to the top wall member 14 of the casing 1 and provided with an arbor 19 having a flanged portion 20 and a stud portion 21. A disk 23 is frictionally held against the flange 20 around the stud 21 by a spring washer 24 or similar device that is held in position by nuts 25 on the stud 21. The disk 3 is secured to the disk 23 by screws 27 and spaced therefrom by a ring or sleeve 28.

10 The disk 3 is provided, on its under surface adjacent to the perimeter thereof, with scale-division marks 30 that correspond to divisions of the diurnal period. A standard 31 depending from the top-wall member 14, carries an index or pointer 32 beneath the disk 3 for cooperation with the scale 30.

15 The electrode 4 comprises a conducting tube 34 that is preferably bent inwardly at its ends and fixed to the disk 3 to rotate therewith. A recording element or pin 35 has portions of different diameters to provide a shoulder 36, in the tube 34, that limits movement of the element 35 in one direction, relative to the longitudinal axis of the tube 34. An adjustable nut 37 on the element 35 limits movement of the latter in the opposite direction. The element 35 is loosely mounted in the tube 34, in substantial floating relation thereto, to move in one direction or the other along the axis of the tube 34 in response to gravity.

20 The plate holder 10 comprises a base plate or member 40 and a rectangular frame member 41 having an inwardly projecting peripheral flange 42 under which a sensitized plate 44 is adapted to be received. A usual opaque plate (not shown) is provided to protect the plate 44 when the holder 10 is not in operative position. A sheet 46 of flexible conducting material lies flat against the underside of the plate 44 and is adapted to be uniformly pressed, throughout its surface area, against the plate 44 by a pad 47 of yieldable material, such as felt. The conducting sheet 46 is secured to the base plate 40, as by a screw 48, and suitably connected to ground. The grounded plate 46 is preferably of circular shape having its outer perimeter extending beyond the path of travel of the electrode 4.

25 The plate holder 10 is received into the casing 1 through an opening 50, in one side wall member of the casing, over which a flexible element or flap 51 is secured, as by screws 52, as protection against the admission of light to the casing.

30 The sensitized plate 44 is initially provided, as by the use of a suitable templet, with chronological markings, similar to those of the scale 30 on the disk 3.

35 In operation, the instrument is initially inverted to permit the recording element 35 to fall, by gravity, out of the path along which the plate holder 10 is to be received.

In this position, the disk 3 is in full view and readily accessible to permit its adjustment by hand to bring any desired mark on the scale 30 into register with the index 32, thus setting the device to the time at which it is 70 desired to begin operation. Also, in the inverted position of the instrument, the clock 2 is accessible for starting. The plate holder 10, carrying the sensitized plate 44, is then inserted in position through the opening 50 and the instrument as a whole, returned to its normal operative position, as shown in Fig. 1. This operation permits the recording element 35 to fall by gravity against the upper sensitized surface of the 80 plate 44 upon the removal of the usual opaque slide. The operation is then begun by connecting the flexible conducting sheet 46 to ground and connecting the terminal 7 to a circuit. Under these conditions, when a voltage surge occurs, it will be recorded on the plate 44, as described in the above mentioned copending application, in a definite position corresponding to the time of occurrence of the surge.

85 The terminal 7 is connected to the system in which the occurrence of a surge is to be detected, through a suitable electrostatic transformer or potentiometer which will, at the normal circuit voltage, establish an electrostatic stress across the plate between the recording electrode 35 and the plate 46 that will be below the critical value at which the plate will be influenced. Upon the occurrence of a surge, however, the value of such stress will be amplified to a value in excess of the critical value of the plate, and a record will be made upon the plate indicative of the character and intensity of the surge.

90 The plate constitutes a dielectric between the recording electrode 35, which is at high potential, when energized, and the ground plate 46, which is at ground potential.

95 While I have shown and described a particular form of my invention, various modifications and changes may be made therein without departing from the spirit and scope thereof and I desire that only such limitations shall be placed thereon as are imposed by the prior art or are set forth in the appended claims.

100 I claim as my invention:

1. A surge recorder including an insulating disk, means for rotating the disk, a space-discharge electrode structure supported by the disk transversely to the plane thereof, an annular contact element supported by the disk and connected to said electrode, and a stationary contact element cooperating with said annular contact element.

105 2. A surge recorder including an insulating disk, means for rotating the disk, a tubular body extending transversely through the disk adjacent to, but slightly displaced from, the outer perimeter thereof, a space-discharge

electrode movable longitudinally in said body, an annular contact element supported on the perimeter of the disk and connected to said electrode, and a stationary contact element cooperating with said annular contact element.

3. An instrument for electrostatically recording the characteristics of surges occurring on an electric circuit comprising an electrically grounded stationary element, a sensitized record chart supported thereon, an electrode-supporting means rotatably supported above said chart for rotation in a plane parallel to the plane of said chart, an electrode carried by said means and adapted to engage the face of said chart, and chronological markings on said record chart and supporting means to permit a desired registration of said electrode with said chart.

20 4. In a surge recorder, the combination with a sensitized record chart, of an electrode relatively movable with respect thereto and operative to record successive steep-wavefront voltage surges on one side of said record chart, means for connecting said electrode to an external circuit, a supporting base member for said chart, a flexible grounded element engaging the other side of the chart and yieldable means between the base member and the grounded element for uniformly pressing the same against the chart.

In testimony whereof, I have hereunto subscribed my name this 26th day of June, 1924.

35 JOSEPH W. LEGG.
